FRANK J. HORTON AND RICHARD W. LEWIS, OF DETROIT, MICHIGAN, ASSIGNEES TO
GENERAL SPRING BUMPER CORPORATION, OF DETROIT, MICHIGAN, A CORPORA-
TION OF MICHIGAN

ABRASIVE APPLYING MACHINE

Application filed July 9, 1930. Serial No. 466,720.

This invention relates to improvements in machines for applying emery or other abrasive to glue-coated grinding wheels. In practice, the wheels are covered on their peripheries with a specially prepared glue, after which they are placed in the machine which is so constructed as to pound the glue-coated periphery into a receptacle containing the heated abrasive, such as emery or the like. The principal object of the invention is to provide such a machine which shall be extremely simple in construction, occupying a minimum of shop space and be very efficient and long-lived. Other and more specific objects will become apparent as the description proceeds.

Fig. 1 is a side elevation showing one of the wheels in position; Fig. 2 is a vertical sectional view taken at right angles to the view of Fig. 1; Fig. 3 is a horizontal section corresponding substantially to the line 3—3 of Fig. 1; and Fig. 4 is a fragmentary section showing the means for adjusting the position of the power unit.

As shown in the drawings, the machine is mounted on a framework 10 which comprises an upper bed portion and suitable supporting legs. Mounted on top of this framework is a channel-shaped steam jacket 11 provided with suitable steam pipes 12 and adapted to serve the double function of supporting a receptacle 13 and maintaining the abrasive material 14 at the proper temperature. Journaled on the underside of the framework bed in bearings 15 is a guide shaft 16 provided at its ends with openings for the reception of wheel supporting rods 17. In addition to passing through the openings in the shaft 16, the rods 17 pass through openings 18 in the framework bed and are provided with shields 19 adapted to prevent abrasive material or dirt from entering the working parts to cause undue wear thereof. At the upper ends of the rods 17 are suitable bifurcated members 20 adapted to receive an arbor 21 to support the grinding wheel 22 to be coated. A power unit is provided for imparting the working motion to the rods 17 and includes a platform 23 pivotally mounted between two of the legs of the framework 10 by means of a

rod 24 passing through the rear edge of such platform and journaled in suitable bosses 25 on the framework. As best seen in Fig. 3, the other end of the platform 23 is supported by a bifurcated portion 26 integral with an upstanding web 27 and cooperating with trunnions 28 on a tapped block 29 supported at any desired height on a screw 30 journaled in the framework in a boss 31 and a web 32 both integral with the framework.

Journaled between two extensions 33 and 34 of the platform 23 is a crank shaft 35 having mounted centrally thereof cranks 37. The lower end of each rod 17 is pivotally connected to a corresponding crank 37 by means of a crank pin 38. A belt 39 serves to connect the motor 40 with the pulley 36 for driving the crank shaft 35 to produce a rolling and pounding movement of the wheel 22.

From the foregoing, it is obvious that we have provided a simple abrasive applying machine, that the abrasive to be applied can easily be kept at the proper temperature by the steam jackets, that the wheel to be coated is given a desirable rolling and pounding action, and that the position of the periphery of the wheel can be adjusted with respect to the abrasive material in the receptacle 13 by means of the hand wheel 41, and that a simple and durable device for effecting the desired result has been provided.

While we have shown and described the preferred form of our invention, we wish it understood that we are not limited to the details disclosed, but may carry out our invention in numerous forms within the scope of the appended claims.

Having thus described our invention, what we claim is:

1. A machine for applying abrasive to a grinding wheel, said machine including means for supporting a mass of abrasive material, and means for supporting said wheel with respect to said mass and imparting thereto such a motion that the periphery of said wheel is pounded into such mass, said last means including a shaft normally fixed with respect to said mass, a crank arm on said shaft, a bar for carrying said wheel and being pivoted on said crank arm, guide means

through which said bar passes, and means for rotating said shaft.

2. A machine for applying abrasive to a grinding wheel, said machine including means for supporting a mass of abrasive material, and means for supporting said wheel with respect to said mass and imparting thereto such a motion that the periphery of said wheel is pounded into such mass, said last means being substantially entirely below the surface of said mass.

3. A machine for applying abrasive to a grinding wheel, said machine including means for supporting a mass of abrasive material, and means for supporting said wheel with respect to said mass and imparting thereto such a motion that the periphery of said wheel is pounded into such mass, the means for supporting the abrasive material being provided with hollow walls whereby steam may be circulated thereabout for heating said abrasive material.

4. A machine for applying abrasive to a grinding wheel, said machine including means for supporting a mass of abrasive material, and means for supporting said wheel with respect to said mass and imparting thereto such a motion that the periphery of said wheel is pounded into such mass, said means for supporting the abrasive material including heating mechanism for keeping the same at proper temperature.

5. In an abrasive applying machine, a supporting framework, an abrasive holding receptacle mounted thereon, a crank shaft rotatably carried by said framework on supporting means; means mounted on said supporting means for rotating said crank shaft, a rod pivoted on a crank on said crank shaft and having means thereon for supporting a wheel to be coated, and a guide in which said rod reciprocates.

6. In an abrasive applying machine, a supporting framework, an abrasive holding receptacle mounted thereon, a crank shaft rotatably carried by said framework on supporting means, means for rotating said crank shaft, a rod pivoted on a crank on said crank shaft and having means thereon for supporting a wheel to be coated and a guide journaled in said framework and constraining motion of said rod.

7. In an abrasive applying machine, a supporting framework, an abrasive holding receptacle mounted thereon, a crank shaft rotatably carried by said framework on supporting means, means for rotating said crank shaft, a rod pivoted on a crank on said crank shaft and having means thereon for supporting a wheel to be coated, a guide carried by said framework and constraining motion of said rod, said supporting means being pivoted to said framework and adjustable about the pivot point to compensate for changes in

amount of abrasive material carried in said receptacle.

8. In an abrasive applying machine, a supporting framework, an abrasive holding receptacle mounted thereon, a crank shaft rotatably carried by said framework on supporting means, means for rotating said crank shaft, a rod pivoted on a crank on said crank shaft and having means thereon for supporting a wheel to be coated, a guide carried by said framework and constraining motion of said rod, said guide including a shaft journaled in said framework and having an opening transversely therethrough receiving said rod.

9. In an abrasive applying machine, a supporting framework, an abrasive holding receptacle mounted thereon, a crank shaft rotatably carried by said framework on supporting means, means for rotating said crank shaft, a rod pivoted on a crank on said crank shaft and having means thereon for supporting a wheel to be coated, a guide carried by said framework and constraining motion of said rod, said guide including a shaft journaled in said framework and having an opening transversely therethrough receiving said rod, and a shield on said rod and covering said opening to exclude foreign material.

10. In an abrasive applying machine, a framework, a channel shaped steam jacket mounted on said framework and adapted to receive therein a receptacle of abrasive material, and mechanism carried by said frame for supporting a wheel and pounding it into the mass of abrasive material in said receptacle.

11. In a machine for applying abrasive to a glue-coated grinding wheel, a supporting framework, means for supporting a mass of abrasive material in fixed relation to said framework, a guide on said framework, rods passing through said guide for carrying the wheel to be coated, and a power unit including a motor and a crank shaft carried by said framework and supporting said rods.

12. In a machine for applying abrasive to a glue-coated grinding wheel, a supporting framework, means for supporting a mass of abrasive material in fixed relation to said framework, a guide on said framework, rods passing through said guide for carrying the wheel to be coated, and a power unit including a platform adjustably and pivotally carried by said framework, and a motor and crank shaft rotatably carried on said platform and connected to said rods.

13. In a machine for applying abrasive to a glue-coated grinding wheel, a supporting framework, means for supporting a mass of abrasive material in fixed relation to said framework, a guide on said framework, rods passing through said guide for carrying the wheel to be coated, and a power unit including a platform adjustably and pivotally car-

ried by said framework, and a motor and crank shaft rotatably carried on said platform and connected to said rods, said crank shaft carrying a pulley and said pulley being
5 connected to said motor.

14. A machine for applying abrasive to a grinding element, said machine including means for supporting a mass of abrasive material, and means for floatingly supporting a
10 grinding element in juxtaposed relation to the abrasive material and imparting to the element such a motion that the periphery of said element is pounded into said material by gravity.

15. 15. In an abrasive applying machine, means for supporting a mass of abrasive material, means for supporting a grinding element, to which said material is to be applied, in juxtaposed relation to said material, the
20 second means including instrumentalities for guiding the element for free upward movement relative thereto, and mechanism for imparting an up and down motion to the second means whereby the element is alternately raised and allowed to descend by gravity
25 into contact with said material.

16. In an abrasive applying machine, means for supporting a mass of abrasive material, means for supporting a grinding element, to which said material is to be applied, in juxtaposed relation to said material, the
30 second means including instrumentalities for guiding the wheel for free upward movement relative thereto, and mechanism for imparting a combined rotary and up and down motion to said means whereby the element is alternately raised and allowed to descend by gravity into contact with said material, with
35 a rolling action.

40 In testimony whereof, we hereunto affix our signatures.

FRANK J. HORTON.
RICHARD W. LEWIS.
